FRED W. OCHES, OF ST. LOUIS, MISSOURI, ASSIGNOR TO WALKER MANUFACTURING COMPANY, OF RACINE, WISCONSIN, A CORPORATION OF WISCONSIN

CAN OPENER DEVICE

Application filed June 24, 1931. Serial No. 546,614.

This invention relates to can openers of the type disclosed in co-pending application, Serial No. 514,877, filed February 9, 1931, in the name of Willis M. Thompson.

5 In this can opener a stationary standard is provided with a fixed journal for a serrated feed wheel which is adapted to engage the underside of the bead present around the rim of the can to be opened and thereby to support 10 the can during the opening operation. A cutting knife is slidably mounted on the standard and a cam moves the knife toward the wheel to puncture the top of the can. A shoulder on the knife blade engages the top 15 of the can to hold the same against the feed wheel.

The depth of the rim bead on different cans varies a few hundredths of an inch and the 20 teeth of the feed wheel wear after extended use, hence there is no one setting of the knife, relative to the feed wheel journal, which will provide the proper pressure between the feed wheel and the knife shoulder for all cans, and if the pressure is too great there will be a 25 binding between the can and the engaging parts of the device which will render the operation of the device difficult or impossible. If the pressure is too light the wheel will not grip the can to feed it positively.

30 The present invention particularly contemplates and has for its object facilitating the operation of the above mentioned device by the provision of a yielding cam which will insure the proper pressure between the can 35 and the feed wheel irrespective of variations in the can bead or in the diameter of the feed wheel.

These objects and others are attained in the 40 structure illustrated in the accompanying drawings in which—

Figure 1 is a side view of the can opener.

Figure 2 is a section taken substantially on line 2—2 of Figure 1.

45 Figure 3 is a detail view showing the cam. The can opener includes an upright standard 1 carried by a horizontal arm 2 which is preferably detachably mounted on a suitable wall bracket 3. The lower end of the standard is provided with a flange 4 which serves 50 as a can guide. A serrated feed wheel 5 is

journaled on standard 1 immediately above guide 4 and has an operating crank 6.

Slidably mounted on the standard above wheel 5 is a carriage 7 having side flanges 8 folded around the edges of the standard, and having outwardly extending top and bottom flanges 9. A knife 10 forms a shouldered extension of, or is rigidly secured to, the lower edge of the carriage and is spaced outwardly from the standard a sufficient distance to 60 penetrate the top of a can 11 having its side wall against guide 4 and having its rim head supported on feed wheel 5.

The knife carriage is operated by means of a cam 12 which rotates on a stud 13 projecting from the standard 1 and extending through a slot 20 in carriage 7. Stud 13 is inserted into an opening 14 in cam 12, the diameter of the opening being greater than the diameter of the stud to provide for relative vertical movement of the cam and stud.

Extending diametrically through cam 12 is a cylindrical opening threaded at its upper end and receiving a plunger 15, a spring 16, and a correspondingly threaded plug 18. Spring 16 thrusts the high part of the cam away from stud 13 and is stiff enough to overcome the resistance of the can to the penetration of the knife and to provide sufficient pressure on the can to insure feeding 80 movement against the knife when the wheel 5 is rotated.

A stop element 19 on arm 2 engages the cam manipulating bar 18 when the knife is in its lowest position and serves to guide the 85 user and to steady the carriage during the cutting operation.

In case the carriage lower flange 9 is engaged by the rim of the can before manipulating bar 18 is lodged against stop 19, as would 90 be the case where the rim of the can were deeper than usual, further rotation of the cam will be possible due to the compression of spring 16 resulting in the raising of the pivotal center of the cam. Thus the cam 95 may be rotated approximately the same amount regardless of the size of the rim of the can being opened, and the operator may easily know when the can is properly engaged for cutting.

By constructing the device so that normal operation thereof will cause some movement of the cam transversely of its stud, the gripping pressure between the feed wheel 5 and flange 9 will be substantially uniform irrespective of differences in the depth of the can beads, wear of the feed wheel or other variations in the device.

Obviously, other yielding means might be substituted for the diametrical spring illustrated and various other elements of the can opener illustrated might be modified without departing from the spirit of the invention and the exclusive use of all such modifications as come within the scope of the appended claims is contemplated.

What is claimed is:

1. In a can opener, a standard, a knife slideable along the same, a cam on said standard adapted to move said knife during the rotation thereof, a stop element arranged to limit the rotation of said cam at a certain position thereof, and a yielding pivotal connection between said standard and said cam and spaced from said stop element whereby said cam may be rotated to said limiting position when further movement of said knife along said standard is resisted, said yielding connection continuing to function when said cam has reached said limiting position.

2. In a can opener, a standard, a carriage slidably mounted thereon and having a can rim engaging element, a knife on said carriage, a cam on said standard adapted during the rotation thereof to move said carriage and said knife to a position in which said element will engage a can in position to be opened and said knife will penetrate the top of said can, and a yielding pivotal connection between said standard and cam whereby variations in the can rim may be accommodated.

3. In a can opener, a standard, a knife slideable thereon, a stud projecting from said standard, a cam engaging said knife and having an opening receiving said stud, said opening being larger than said stud, and yielding means in said opening and compressed between said stud and said cam whereby the pivotal center of said cam may be changed under abnormal pressure on said cam to permit said cam to be rotated to a desired position.

4. In a can opener, a standard, a feed wheel pivoted thereon to support a can, a member slidably mounted on said standard and having a shoulder to engage the can to thrust it against said wheel, a blade on said member adapted to cut the top of the can, a cam operatively engaging said member, a stud on said standard, said cam having an opening larger than said stud and loosely receiving the same, and a spring extending substantially diametrically through said cam and compressed between said stud and cam,

said spring being adapted to maintain said stud in engagement with the side of said opening during the initial movement of said cam and knife, and to yield when the shoulder on said knife is engaged by the can where-
the consequent movement of the pivotal center of said cam will permit further rotation of said cam.

5. In a can opener, a standard, a knife carriage slideable thereon, a self adjusting cam pivoted on said standard for moving said carriage, the mounting of said cam including a pivot stud on said standard passing through a larger hole in said cam, there being a recess in said cam intersecting said hole, a bearing in said recess for engaging said stud, a plug threaded into said recess, and a spring compressed between said bearing and plug.

In testimony whereof I hereunto affix my signature this 13th day of June, 1931.

FRED W. OCHEZ.
